UNITED STATES PATENT OFFICE.

JAMES B. RYER, OF NEW YORK, N. Y.

DESIGN FOR WOVEN FABRICS.

SPECIFICATION forming part of Design No. 11,580, dated January 13, 1880.

Application filed December 19, 1879. Term of patent 3½ years.

To all whom it may concern:

Be it known that I, JAMES B. RYER, of New York city, in the State of New York, have invented, originated, and designed a new Patent for Woven Fabrics, intended more especially to be produced in the loom by the use of previously-colored yarns, of which the following is a full, clear, and exact description, reference being had to the accompanying illustration, making part of this specification, which fully represents said design, and is sufficient without further aid to enable any person skilled in the art to repeat it for practical use.

The colors employed for the different portions of this design may be varied to suit the convenience or taste of the manufacturer.

What I claim as my design, and desire to secure by Letters Patent, is—

The design for woven fabrics, as shown. 20

In testimony whereof I have hereunto set my hand.

JAMES B. RYER.

Witnesses:
